CLAIM

I claim the ornamental design for a grill, as shown and described.

DESCRIPTION

FIG. 1 is a perspective view of a grill, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view thereof; and,

FIG. 9 is a cross sectional side view along line 9-9 in FIG. 6.
